DISPENSING TOP FOR CONTAINERS

Ralph V. Burdick, Albany, N. Y.

Application July 25, 1935, Serial No. 33,119

4 Claims. (Cl. 221—62)

This invention relates generally to dispensing containers or the like, and more specifically comprehends the provision of a novel construction of a sifter top therefor.

5 The most commonly known sifter container in present day use, primarily consists of a perforated neck normally closed by a removable or swivel cap. There are of course various types of caps employed in this connection, but irrespective of the particular construction employed, it is necessary to use both hands in either opening or closing the container.

In addition to the above, there is another type of dispensing container known to the art, to 15 which the present invention relates, wherein use is made of a perforated shutter mounted upon the outer end of the neck of the container and subsequently encased in a stationary cap. The cap is crimped or otherwise permanently connected to the neck and utilized in part to maintain the shutter in place. These constructions not only entail an assembly cost of vital importance, but have not proven satisfactory, unless made in brass, which materially enhances the 20 cost of manufacture. Consequently they have never been put into general use.

It is therefore one of the principal objects of the present invention to provide a novel construction of a sifter top for containers capable 30 of being easily and conveniently manipulated by one hand, and which forms a permanent part of the container, thereby eliminating the trouble and annoyance usually resulting from dropping, losing, or misplacing a removable part.

35 An equally important object of the invention resides in the provision of a sifter top construction primarily intended to be made from tin plate, and one which possesses the same high degree of efficiency and smoothness in operation, 40 as it would if made from brass, together with a material reduction in the cost of manufacture.

In carrying out the invention I comprehend the use of a perforated shutter associated with the neck of the container in a novel and unique 45 manner, whereby the assembly cost is materially reduced by the elimination of certain operations necessary in other containers of the type above referred to in order to maintain the component parts thereof operatively associated.

Another object of the invention resides in the novel construction of a container top of the class in question which is not only attractive in appearance, capable of being manipulated by one 50 hand, but one wherein the casual sifting or loss

of the contents of the container is reduced to a minimum.

Other objects and advantages will appear when the following detail description is read in connection with the accompanying drawing, the invention residing in the construction, combination and arrangement of parts as claimed.

In the drawing forming part of this application like numerals of reference indicate similar parts in the several views and wherein:

Figure 1 is a fragmentary side elevation of a container embodying the invention.

Figure 2 is a fragmentary top plan view.

Figure 3 is a sectional view on line 3—3 of Figure 2.

Figure 4 is a similar view of a slightly modified construction.

Figure 5 is a perspective view of the shutter.

Figure 6 is a perspective view of the inner shell.

While I have illustrated and described the instant invention as a dispensing top, primarily intended for powder containers or the like, its general application as a sifter top for other types of containers is contemplated by the claims.

The dispensing top embodying the subject 25 matter of the instant invention may of course be made from brass or any other suitable material, although it is primarily intended to be constructed from tin plate possessing the same high degree of smoothness and efficiency in operation 30 it would possess if constructed from more costly material. The invention essentially embodies a relatively long outer shell 10, constituting the neck of the container as illustrated, a comparatively short inner shell 11 and a rotatably mounted shutter 12. The outer shell 10 is formed with a perforated end wall 13, which of course may be provided with one or more perforations of any suitable outline from which the contents of the 35 container are dispensed. The wall of the outer shell 10 may be straight at its point of juncture with the end wall 13 as shown in Figures 1 and 3, or it may be characterized with a laterally projecting bulge or bead 14 at this point as indicated in Figure 4. In either event the wall of the outer shell 10 immediately adjacent the end wall 13 is formed with a slot 15, the purpose of which will be presently set forth.

The inner shell 11 is snugly fitted within the outer shell 10 and supported thereby in juxtaposition with the end wall 13 thereof. The inner shell 11 is provided with a perforated end wall 16 slightly spaced from the perforated end wall 13 of the outer shell, and the perforations of these respective end walls 13 and 16 of said 50 55

shells are disposed in registration with each other. The inner shell 11 is proportioned to provide for a driving fit within the outer shell 10, whereby these component parts are held associated by friction, thus eliminating a crimping operation or any additional means whatsoever to maintain the parts operatively related.

Operating between the perforated end walls 13 and 16 of the respective shells is a perforated shutter 12 mounted for partial rotation, and of course utilized to control the discharge of the contents of the container. Projecting laterally from the shutter 12 is a finger engaging lug 17 for operating the shutter, and obviously this lug operates through the slot 15 of the outer shell. The length of the slot 15 limits the rotary movement of the shutter in either direction, so that when the latter is turned in one direction its perforations are brought into registration with the perforations of the end walls 13 and 16 of said shells, and when shifted in a reverse direction the perforations of the shutter are moved out of registration with the perforations of said end walls 13 and 16, thereby effectively closing the container. The shutter 12 is snugly fitted between the end walls 13 and 16 of said shells, but is held centralized to insure a smooth and efficient operation thereof.

For this purpose the end wall 16 of the inner shell is preferably formed with a cone like depression 18 constituting a bearing for the pivot 19 depending from the shutter 12 as clearly illustrated. It is to be particularly observed that the inner shell 11 and shutter 12 are fitted with in the outer shell and frictionally maintained operatively related. Consequently by the elimination of any and all crimping operations, or the use of any additional means to hold the component parts of the top associated, it is manifest that not only is the assembly cost of manufacture materially reduced, but a very smooth and efficient operation of the shutter provided for, with casual sifting or loss of the contents of the container reduced to a minimum. The shutter 12 is frictionally maintained in either of its two given positions. It is by virtue of the construction and novel association of the component parts of the top that the latter can be manufactured from tin plate and possess the same degree of smoothness and efficiency in operation as it would possess if made from more costly material. Furthermore, it will be noted that the top in its entirety forms an integral part of the container, having no removable parts, and one that can be very conveniently manipulated by one hand.

While it is believed that from the foregoing description the nature and advantages of the invention will be readily apparent, I desire to

have it known that I do not limit myself to what is herein illustrated or described and that such changes may be resorted to when desired as fall within the scope of what is claimed.

What is claimed is:

1. A dispensing top for containers or the like including an outer shell having a perforated end wall and constituting the neck of the container, a comparatively short inner shell having a driving fit within the outer shell and frictionally supported by the wall of the latter, said inner shell having a perforated end wall disposed in spaced confronting relation with the end wall of the outer shell, a perforated shutter rotatably mounted between the respective end walls of said shells, and means whereby said shutter is operated.

2. A dispensing top for containers or the like including an outer shell having a perforated end wall and constituting the neck of the container, a comparatively short inner shell frictionally supported by the wall of the outer shell and having a perforated end wall disposed in close proximity to the end wall of the outer shell, a perforated shutter pivotally mounted between the respective end walls of said shells and frictionally maintained in a given position, and means whereby said shutter is operated.

3. A dispensing top for containers or the like including an outer shell having a perforated end wall and a slot and constituting the neck of the container, a comparatively short inner shell snugly fitted within the outer shell and frictionally supported by the wall of the latter, said inner shell having a perforated end wall disposed in close proximity to the end wall of the outer shell, a perforated shutter rotatably mounted between the respective end walls of said shells and having a centralizing pivot, and a finger engaging lug projecting from the shutter and operating in said slot.

4. A dispensing top for containers or the like including an outer shell having a perforated end wall and a slot and constituting the neck of the container, a comparatively short inner shell frictionally supported by the wall of the outer shell and having a perforated end wall disposed in close proximity to the end wall of the outer shell, said end wall of the inner shell having a central depression constituting a bearing, a perforated shutter rotatably mounted between the respective end walls of said shells and frictionally maintained thereby in a given position, a pivot depending from said shutter and operating in said bearing, and a finger engaging lug projecting from the shutter and operating in said slot.
